UNITED STATES PATENT OFFICE.

ALLAN B. HENDRICKS, JR., OF PITTSFIELD, MASSACHUSETTS, ASSIGNOR TO GENERAL ELECTRIC COMPANY, A CORPORATION OF NEW YORK.

WATER-COOLED ELECTRICAL APPARATUS.

1,394,899.

Specification of Letters Patent. Patented Oct. 25, 1921.

Application filed February 24, 1920. Serial No. 360,912.

To all whom it may concern:

Be it known that I, ALLAN B. HENDRICKS, Jr., a citizen of the United States, residing at Pittsfield, in the county of Berkshire, State of Massachusetts, have invented certain new and useful Improvements in Water-Cooled Electrical Apparatus, of which the following is a specification.

My invention relates to water cooled electrical apparatus, or to incased apparatus which in addition to the main cooling and ventilating medium circulating in the casing employ an auxiliary medium, such as water, to cool the main medium.

My invention has for its general object an improved arrangement of parts whereby a smaller, cheaper, and better cooled apparatus results than has heretofore been obtainable from the practices of the prior art.

Further objects of my invention are to provide an arrangement of parts affording a rapid circulation of the main cooling medium such as oil, whereby the electrical apparatus is rapidly cooled as a whole; also to eliminate the air space in the apparatus casing commonly occurring above the oil and thereby avoid the attendant evils such as sludging; and to provide a compact and improved auxiliary oil reservoir in the casing, such as are commonly styled "oil conservators" in the prior art.

In electrical apparatus equipped with auxiliary cooling systems, for instance water circulating means, it has been customary to provide tanks or casings of great height, as compared with that of the apparatus within the tank, in order to provide sufficient head to insure the desired circulation by gravity of the main cooling medium, the coils in which circulates the auxiliary medium being more or less confined to the upper portions of such tanks. This practice has resulted in tall, bulky and expensive apparatus.

In the practice of my invention I avoid these shortcomings by employing a tank that is relatively not much higher than the electrical apparatus to be housed and arrange the apparatus within the tank in a manner to insure a sufficiently rapid circulation of both the main and auxiliary cooling mediums to secure the desired cooling effect without resort to the great head of main cooling medium heretofore employed. This decrease in size of the tank employed to-

gether with other advantageous arrangements which I will presently describe fully in detail enable me to accomplish the objects of my invention as above set forth.

A more complete understanding of the nature and objects of my invention may be had from the following description taken in connection with the accompanying drawing in which:

Figure 1 shows in perspective a tank for transformers and the like constructed in accordance with my invention. Fig. 2 is a view, mainly in vertical section, showing details in the tank construction. Fig. 3 is a perspective view of the cooling coil removed, such as I employ in connection with my invention; and Fig. 4 is a fragmentary sectional view showing coöperating details of the winding on the electrical apparatus, which are employed to accomplish the improved cooling effect of my invention.

Referring now to the drawing, A represents generally the tank, which in large capacity apparatus is as a rule mounted on a movable base or frame, such as shown at B; such base for this purpose being provided with wheels C.

The tank A is shown as containing a transformer T whose core 11 is but a little below the cover of the tank. About this transformer, adjacent the sides of the tank A are the cooling coils 12 which extend along the wall substantially from the top of the tank to a point adjacent the bottom which is at about the same height above it as the lowermost coil of the winding, such winding being shown at 13 on the transformer shown in the drawings.

In order to provide a large and rapidly moving volume of auxiliary cooling medium, such as water, to cool the oil or main medium in the tank, I preferably employ a plurality of coils, here shown as two, connected to convey parallel streams of the medium. The inlets for these two coils are shown at 14 and 15 in Fig. 3; the coils leading therefrom being arranged in interior and exterior spirals 16 and 17.

By means of this parallel arrangement of the spirals of the cooling coil and by making them of relatively small diameter, the medium circulating therein is adapted quickly to absorb large quantities of heat.

The convolutions of these spirals are se-

cured by means of suitable clamps, shown at 18, bolted to a number of uprights 19 which are removably secured to the wall of the tank A. The coils as a whole may thus 5 be bodily removed from the tank A when the securing devices have been unloosed, and the inlets 14 and 15, and outlets 20 and 21 removed from their stuffing glands, such as shown at 22 in Fig. 1, which are provided 10 therefor in the walls of the tank.

The winding 13, in order to coöperate in achieving the rapid cooling effect of my invention, is designed to deflect, at a plurality of points, the circulating oil so that it impinges directly against the coils 12 in parallel streams. This is accomplished by locating suitable baffles, as shown at 25 in Fig. 4, among the turns of the winding, which winding is preferably composed of horizontal 15 disk-coils. The oil which flows in, in large 20 volume over the spacers 26 at the base of the winding stack, is deflected outward against the cooling coils in a plurality of superposed streams substantially throughout the 25 whole height of the cooling coils. In this manner the heat generated in the winding 13 is quickly dissipated and to this end the clearances between the winding and the cooling coils are made as small as is electrically 30 permissible.

As before pointed out, in cooling in accordance with my invention relatively little head of oil to induce gravity circulation of oil, is employed by me; hence the cover for 35 the tank is placed as close to the top of the electrical apparatus within the tank as is electrically feasible, the oil level reaching up to the cover. To provide for the expansion and contraction of the oil under these 40 circumstances, I form the cover itself with an expansion chamber 30, the oil level within this chamber being indicated at S, a float device as at 31 being conveniently employed to indicate this level on the exterior of the 45 tank. The communication between the interior of chamber 30 with tank A is preferably guarded by a suitable trap as indicated at 32 to prevent the passage of water or

sludge, which may accumulate in chamber 30, from entering the tank A. 50

Having now described an embodiment of my invention which is at present the best means known to me for carrying the same into effect, I would have it understood that this is merely illustrative and that I do not 55 mean to be limited thereby to the precise details shown, nor restricted in the choice of recognized equivalents except as defined in my claims hereunto annexed.

What I claim as new and desire to secure 60 by Letters Patent of the United States, is:

1. In incased electrical apparatus having main and auxiliary cooling mediums, the combination with cooling coils, of a winding arranged in close proximity thereto having 65 means arranged to deflect laterally the vertically rising streams of the main medium against said coils in a plurality of parallel streams.

2. In incased electrical apparatus having 70 main and auxiliary cooling mediums, the combination with cooling coils arranged to conduct a plurality of parallel streams of auxiliary cooling mediums, of a winding adjacent thereto and means interleaved therewith arranged to deflect the main medium against said coils in a plurality of superposed parallel streams. 75

3. The combination with a casing, of an electrical apparatus having a winding composed of coils spaced apart to form ventilating passages housed therein and adapted to be cooled by a main medium contained in said casing, cooling coils for an auxiliary medium distributed along the walls of said 80 casing opposite said ventilating openings, and a chambered cover for said casing having a centrally depressed bottom below the level of said main medium; the chamber being adapted to serve as an expansion chamber for said main medium, and the bottom 85 to serve as a top deflector for the vertically rising streams of main medium. 90

In witness whereof, I have hereunto set my hand this 19th day of Feb., 1920.

ALLAN B. HENDRICKS, JR.
